UNITED STATES PATENT OFFICE.

CHARLES L. PEIRCE, JR., OF PITTSBURGH, PENNSYLVANIA.

INSULATOR-SUPPORTING FIXTURE.

1,175,078.

Specification of Letters Patent. Patented Mar. 14, 1916.

Application filed May 4, 1914. Serial No. 836,116.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Insulator-Supporting Fixtures, of which the following is a specification.

My invention relates to insulator supporting fixtures and involves improved construction.

The purpose of the invention is to provide a strong, inexpensive fixture particularly adaptable for supporting the conductors of high tension circuits and which can be readily secured in place, as for example on a pole, with a minimum of labor and expense and without the need of gaining the pole.

More in detail, the invention contemplates the construction of fixtures of pipe lengths rigidly secured together by strong and durable castings which are curved to accurately fit the surface of the supporting pole.

The various features of the invention are clearly shown on the accompanying drawing in which--

Figure 1 is an elevational view of one of my improved fixtures and one end of the pole to which the fixture is secured, and Fig. 2 is a top view of the fixture and pole.

The fixture shown is of anchor shape comprising the vertical straight part 5 preferably in the form of an ordinary pipe, and the U-shaped lower transverse part formed by the L-shaped brackets 6 and 6', the ends 7 and 8 of which, and the end 5' of the part 5, are tapered and provided with any desired form of insulator receiving thimble 9, the thimbles shown in this case being in the form of wire helices. To secure the parts 5, 6 and 6' together I provide a fitting 10 preferably in the form of a casting comprising a back a, a horizontal sleeve b, and the vertically extending sleeve or flange c. As shown, the unshaped parts 6 and 6' seat at their inner ends in the ends of sleeve b and are securely held therein by pins 11 and 11'. The sleeve c receives the lower end of the part 5 which is secured therein by a pin 12. In order to secure the fixture to a support such as a pole z, a bolt hole 13 is provided through the fitting and through the part 6 for receiving a bolt 14. The part 5 above the fitting has also a bolt hole 15 for receiving a bolt 16, and these bolts preferably ex-

tend entirely through the pole. In order that the fitting may more accurately fit the pole, the back of the base a of the fitting is rounded as shown in Fig. 2. The fixture is preferably applied close to the top of the pole so that the insulator supporting end of the part 5 will clear the top of the pole. After assembly of the fixture it is preferably galvanized both inside and out and will then be efficiently protected against the weather and its life greatly prolonged.

The fixture shown and described is of inexpensive yet durable construction and its rounded fitting together with the through bolts will insure secure, rigid mounting thereof on the pole. Any kind of insulator support may, of course, be used for the insulator supporting ends of the fixture or the ends of the fixture may be threaded or otherwise treated to directly receive insulators. Instead of using ordinary pipe, solid metal or metal of any other shape may be used. I do not therefore desire to be limited to the precise construction, form and arrangement shown as changes may readily be made which would still come within the scope of the invention.

I claim as follows:

1. An insulator supporting fixture comprising a vertical length of pipe, a fitting to which the lower end of said pipe is secured, bracket sections secured to and extending laterally from said fitting, the ends of said bracket sections and the upper end of said vertical length being adapted to support insulators, said fitting having a bolt hole and having a rounded base for fitting the curvature of a pole to which the fixture is to be secured.

2. An insulator supporting fixture comprising a vertical length of pipe, a fitting to which the lower end of said pipe is secured, bracket sections secured to and extending laterally from said fitting, the ends of said bracket sections and the upper end of said vertical length being adapted to support insulators, there being a bolt hole through said fitting and through said vertical pipe length for receiving bolts to secure the fixture to a pole, the base of said fitting being rounded to fit the pole surfaces.

3. An insulator supporting fixture comprising a pipe fitting having a vertical socket and lateral sockets, a vertical pipe section secured at its lower end in said ver-

tical socket, and L-shaped pipe sections secured at their inner ends in the lateral sockets, said fitting being adapted to be secured to a support and the ends of the vertical section and the L-shaped sections being adapted to receive insulators or insulator supports.

In witness whereof, I hereunto subscribe my name this 27th day of April, A. D. 1914.

CHARLES L. PEIRCE, JR.
